UNITED STATES PATENT OFFICE

WILLIAM TULLY, OF LONDON, ENGLAND.

APPARATUS FOR SECURING BOILER-TUBES.

SPECIFICATION forming part of Letters Patent No. 233,050, dated October 5, 1880.

Application filed August 26, 1880. (No model.) Patented in England October 21, 1879.

To all whom it may concern:

Be it known that I, WILLIAM TULLY, a subject of the Queen of Great Britain, residing at the city of London, England, have invented 5 certain new and useful Improvements in Apparatus for Securing Boiler-Tubes, of which the following is a full, clear, and exact description.

My invention has for its object to provide an 10 improved and simple implement or apparatus for securely fastening the ends of boiler or other tubes within the apertures provided for them in the plates or other pieces which are to hold the said tubes in proper position in a 15 steam-boiler or other structure.

My invention is fully illustrated in the accompanying drawings, in which—

Figure 1 represents a side elevation of my 20 improved implement or apparatus, and Fig. 2 is a longitudinal central section of the same.

In the accompanying drawings, the letter A indicates a hollow cylinder, made in two sections, b c, which are joined together by a tenon, 1, on one section fitting a socket, 2, in the other 25 section, for a purpose to be hereinafter explained. The front end of the cylinder-section c is provided with three or more dovetailed recesses, 3, into which are fitted the dovetailed projections or shanks f² on the lugs or pieces 30 f. These three or more lugs or pieces f are provided with flanges, rims, or shoulders f', and are so constructed that they form so many segments of a circle, and when not expanded they fit closely together, so that a cylindrical 35 piece is provided with an annular projecting flange at the rear thereof, and with a central aperture, within which works the tapering or conical end e' of a mandrel, e. This mandrel e fits snugly within the cylinder, and at its 40 rear end it is provided with a screw-threaded shank, e², upon which is screwed a cap, e³, which confines in place the annular head or disk p² of a screw-threaded rod, p. The screw-rod passes through the cap e³ and through a 45 screw-threaded opening in a nut or cap-piece, p', screwed upon the rear end of the cylinder-section b, whereby said screw-rod can freely rotate without rotating the mandrel.

The screw-rod is provided with an angular 50 head, to which a wrench may be applied for rotating the rod and moving the mandrel for-

ward and backward; but other mechanical means may be substituted for such angular head.

By screwing the rod p inward the mandrel 55 is forced forward, and the segments f caused to move radially—that is to say, at right angles to the axis of the cylinder.

In the implement thus constructed the cylindrical piece formed by these segments f is 60 designed to be inserted within the end of a boiler-tube with the annular rims or flanges f' abutting against the outside of the tube, which thus forms a support for the implement, and prevents its entering the tube farther than is 65 required.

When the lugs or segments are caused to slide outwardly by the action of the mandrel they necessarily become separated; consequently there are three or more openings or 70 spaces between the segments, so that there will be corresponding portions of the internal surface of the tube not in contact with any portion of the segments, unless the segments are caused to have a slight rotation. I therefore 75 provide the internal surface of the cylinder-section c with inclined grooves or chambers c*, corresponding with projections e*, provided upon the surface of the mandrel e, and the said mandrel is provided with a pin, e², which slides 80 freely in a groove, e³, in the inside of the cylinder-section b, but prevents any rotary movement of the said mandrel when moved longitudinally. It will thus be seen that whenever 85 the latter is moved forward the cylinder-section c has imparted to it a slight rotary movement, of which the segments f partake. By this arrangement the entire inner surface of the tube which is around the segments f is 90 operated upon by the latter when they are expanded, and the tube is expanded evenly, and any projections in the metal are pressed out and a firm joint is made. To provide for this slight rotation of the cylinder-section c, I provide it with screws l, which fit within slots 95 l' in the tenon 1 of the section b, which slots are made of sufficient length to allow the section c to rotate the required distance.

Having fully described my invention, what I claim is—

1. An implement for expanding tubes in which are combined, substantially as herein

described, a hollow cylinder, made in two sections, one of which carries at its front edge a series of radially-movable flanged segments, a mandrel arranged within the cylinder, a screw-rod passing through a screw-threaded opening in the rear portion of the cylinder and having its inner end loosely connected with the mandrel, and means for imparting a rotating movement to the section of the cylinder which carries the segments, all substantially as described.

2. In a tube-expander, the combination of the cylinder-sections *b* *c*, connected together so as to permit the latter to have a slight rotation, the section *c* carrying a series of radially-movable flanged segments, *f*, and pro-

vided on its inner surface with inclined grooves *c**, with the tapering or conical mandrel *e*, having the inclined projections *e**, screw-shank *e*†, and cap *e*‡, and the screw-rod *p*, passing through a screw-threaded opening in the rear end of *b* 20 the cylinder-section *b*, and having a head or disk, *p*§, loosely connected with the mandrel by the cap *e*‡, all substantially as herein shown and described.

In testimony whereof I have hereunto set 25 my hand in the presence of two witnesses.

WILLIAM TULLY.

GEORGE H. GRAPES.

UNITED STATES PATENT OFFICE
CERTIFICATE OF CORRECTION

Patent No. 233,050 Dated October 1, 1974

Inventor(s) Richard S. Young, and Leo E. Hearn

It is certified that error appears in the above-identified patent and that said Letters Patent are hereby corrected as shown below:

Delete Figures 1a - 6a from the drawings.
